No. 740,321.

PATENTED SEPT. 29, 1903.

A. J. SHAUL.
ACCOUNT BOOK HOLDER.
APPLICATION FILED JULY 16, 1902.

NO MODEL.

UNITED STATES PATENT OFFICE.

ALBERT J. SHAUL, OF QUIMBY, IOWA.

ACCOUNT-BOOK HOLDER.

SPECIFICATION forming part of Letters Patent No. 740,321, dated September 29, 1903.

Application filed July 16, 1902. Serial No. 115,886. (No model.)

To all whom it may concern:

Be it known that I, ALBERT J. SHAUL, a citizen of the United States, residing at Quimby, in the county of Cherokee and State of Iowa, have invented a new and useful Improvement 5 in Account-Book Holders, of which the following is a specification.

My improved device is adapted for holding account and other books for containing records of more or less value and which when not in use require to be deposited in safes or vaults. Several holders proper are assembled in groups or series and slidably connected in such manner that when the account-books 15 placed therein are required for use the holders may be adjusted one on the other so as to project one above another and be adapted for support in vertical position upon a desk suitably constructed with a series of ledges 20 or shelves of a width corresponding to that of the individual holders. Such stepwise adjustment permits the top or upper portions of the several account-books to be conveniently inspected, and the names of the several parties 25 with whom the accounts are kept being printed on such portions a selection of any one of the books may be instantly made. The several holders of a group or series may be readjusted from such extended form or 30 position into a compact form, so as to occupy minimum space when placed and stored in a safe or vault, without removal of the account-books.

The details of construction, arrangement, 35 and operation are as hereinafter described, and illustrated in accompanying drawings, in which—

Figure 1 is a perspective view of a desk with a series or group of my improved account-book holders placed in position thereon as required for use. Fig. 2 is a transverse vertical section of a portion of such desk and several of the holders placed thereon. Fig. 3 is a perspective view of one of the plates composing 45 an individual holder. Fig. 4 is a perspective view of the other plate composing part of an individual holder. Fig. 5 is a horizontal section of a portion of the desk and a series of holders. Fig. 6 is a vertical section 50 of a series of holders adjusted in compact form, as required for storage.

In Fig. 3 one of the plates, A, composing one

of my book-holders is shown in the form it assumes when connected with the other plate, B. (Shown in Fig. 4.) The plate A is rectangular and provided at its top edge with a downwardly and forwardly bent portion, forming a lip or flange a, and at the bottom edge with two corner-flanges a', which are similarly bent forward and upward, and with an intervening horizontal ledge a², which in practice forms the bottom of an individual book-holder and serves as a support for a book. The plate B (shown in Fig. 4) has inwardly-bent side flanges b. When the two parts A B are placed together and connected, as shown in Figs. 1, 2, 5, 6, the flange a of plate A overlaps or hooks upon the top edge b' of plate B, while the bottom flanges a' of plate A similarly engage the bottom edge of plate B. The side flanges of plate B engage the side edges a³ of plate A, as will be apparent by inspection of Fig. 5. As will be apparent upon due inspection, the said flanges b are of less length than the plate A, and consequently the parts 75 A B are adapted to slide upon each other lengthwise to the extent which this difference permits. This slideable connection adapts the series or group of holders to be adjusted in stepwise relation, or one above another, 80 as shown in Figs. 1 and 2, where they are shown with the bottom a³ resting directly upon the ledges or shelves c of the desk C. The account-books x, which are placed in the several individual holders, as shown in Fig. 85 1, are ordinarily of greater length than the holders, so that the projecting portion may be inscribed with the name of the party with whom the account is kept, and the stepwise adjustment and relation of the several members of the group or series of holders permits 90 convenient visual inspection of the corresponding group or series of account-books, so that any one may be instantly selected when required for use. The slideable connection 95 before described between the plates A B enables the several members of a group of holders to be adjusted as shown in full lines, Fig. 6, where the tops and bottoms are in the same plane, the holders thus assuming the most 100 compact form and occupying the minimum space. When so adjusted, the series or group of holders are placed in a safe or vault without removing the account-books therefrom.

The sloping front portion *c'* of the desk C affords a convenient surface or support upon which to lay and inspect any account-book removed from the holder.

5 What I claim is—

1. The improved account-book holder comprising a series of connected book-receptacles formed of a rectangular plate having top and bottom flanges and a horizontal bottom ledge, 10 and a second plate having inwardly-bent side flanges which embrace the side edges of the first-named plate, the flanges of the latter similarly engaging the top and bottom edges of the second plate, substantially as shown 15 and described.

2. The improved account-book holder comprising two rectangular plates having top,

bottom and side flanges and a bottom ledge as described, the side flanges of the one engaging the side edges of the other and being 20 adapted to slide thereon, to permit adjustment of the series of holders in stepwise relation, as and for the purpose specified.

3. An improved account-book holder comprising a series of individual holders the same 25 being constructed of a plate having top and bottom flanges and a bottom ledge, and a second plate having side flanges, the first-named plate forming in each case the front side of a holder, substantially as shown and described. 30

ALBERT J. SHAUL.
